UNITED STATES PATENT OFFICE.

JOHN VAUDREUIL, OF MILWAUKEE, WISCONSIN.

DOOR-LATCH.

1,298,266.

Specification of Letters Patent. Patented Mar. 25, 1919.

Application filed March 18, 1918. Serial No. 223,103.

To all whom it may concern:

Be it known that I, JOHN VAUDREUIL, a citizen of the United States, and resident of Milwaukee, in the county of Milwaukee and 5 State of Wisconsin, have invented certain new and useful Improvements in Door-Latches; and I do hereby declare that the following is a full, clear, and exact description thereof.

10 This invention relates to a fastening device and has for its principal object to provide a simple, cheap and efficient device especially adapted for use on automobile doors.

15 My invention has for one of its objects to provide a door catch which will permit the door to be released without the use of a knob or handle and which, due to its peculiar construction requires greater effort to 20 open than to latch thereby insuring the door being held in its latch position until it is desired to open the same.

Another feature of the invention is to 25 provide a spring door catch of this nature with means for increasing the tension of the spring as the same deteriorates from continual use.

The invention in one practical form in 30 which it may be embodied is illustrated in the accompanying drawings, in which:

Figure 1 is a sectional view through a door-jamb showing the construction of my latch as indicated by the line 1—1 of Fig. 2, and

35 Fig. 2 is a side elevational view of a door-jamb with parts broken away and in section to more clearly illustrate the invention.

In the drawings 1 is a door member of a common construction employed in automobile bodies. The wood filler 2 is cut out to receive the latch casing 3 which has movably mounted therein a bolt 4, provided with an opening into which is nested a coiled spring 5. The inner end of the casing 3 is provided 40 with a closure 6 which is cut out to form openings 7 to permit the arms 8 of the bolt member to pass through the closure. Threaded into the closure 7 is a screw 9 which at its inner end abuts the block 10 45 against which the coiled spring 5 is seated.

It will be readily seen that the coiled spring 5 will at all times urge the bolt member 4 outwardly until its inner end abuts the closure member 7. One of the greatest disadvantages of a latch of this nature is in 55 the fact that the tension of the spring rapidly deteriorates due to the continual use. This is readily overcome by the use of a screw 9 which, upon deterioration of the spring tension, can be turned in against the 60 block 10 thereby increasing the tension of the spring to any desired amount.

Screwed to the door-jamb 11 is a striker plate 12, which in the present instance, I have shown to conform to the shape of the 65 engaging end of the bolt member 4, but which can be made in various ways without affecting the operation of my latch.

The engaging end of the bolt 4 is provided with two cam surfaces X and Y of different 70 pitch. The cam surface Y, being the surface which comes into contact with the striker plate 12 when the door is to be closed, is struck upon a much smaller arc than the cam surface X which works against the 75 striker plate upon forcing the door outward. From the foregoing description it will be readily seen that a much greater effort is required to force the door outward from its latched position than to close the same. 80 While I have shown the cam surface X and Y as struck on an arc, it will be appreciated that I might make these surfaces flat and of different pitch without departing from the invention.

To prevent accidental opening of the door when the same is not desired a locking pin 13 is provided having one of its ends crank-shaped and adapted to be positioned in the slot 14 formed in one side of the locking 90 bolt. When the locking pin is in its normal position, as shown in the drawing, the bolt is free to move in either direction. Upon turning the pin in a clockwise direction the crank end of the pin will drop into a notch 95 15 formed at one end of the slot thus locking the bolt against movement.

What is claimed is:

In a latch of the class described, a casing, a bolt slidably mounted in the casing and 100

provided with a longitudinal recess, a stop member for said bolt carried by the casing extending into the longitudinal recess and engageable with the rear end of the recess to limit forward sliding movement of the bolt, an adjusting screw slidably passed through the rear portion of the bolt and threaded in the stop member and a spring in-

terposed between said adjusting screw and the forward end of the recess.

In testimony that I claim the foregoing I have hereunto set my hand at Milwaukee, in the county of Milwaukee, and State of Wisconsin.

10

JOHN VAUDREUIL.
